Primary Examiner — Terry Wallace*Assistant Examiner* — Dana L Meyrow*(74) Attorney, Agent, or Firm* — Fitch, Even, Tabin & Flannery LLPCLAIM

The ornamental design for a bottle, as shown and described.

DESCRIPTION

FIG. 1 is a perspective view of a bottle showing our new design;

FIG. 2 is a front elevational view thereof, the rear elevational view being an identical image;

FIG. 3 is a top plan view thereof;

FIG. 4 is a right side elevational view thereof, the left side elevational view being an identical image; and,

FIG. 5 is a bottom plan view thereof.

Portions of the bottle shown in broken lines in the figures are for illustrative purposes only and form no part of the claimed design.
